UNITED STATES PATENT OFFICE.

CLARENCE BENTON JORDIN, OF CLE ELUM, WASHINGTON.

CURRENT MOTOR.

Application filed June 9, 1921. Serial No. 476,239.

To all whom it may concern:

Be it known that I, CLARENCE B. JORDIN, a citizen of the United States, residing at Cle Elum, in the county of Kittitas and 5 State of Washington, have invented certain new and useful Improvements in Current Motors; and I do declare the following to be a full, clear, and exact description of the invention, such as will enable others 10 skilled in the art to which it appertains to make and use the same.

My invention relates to improvements in current motors and more particularly to those which are anchored near the bed of 15 a stream or river, so as to be unaffected by tides, drift-wood, etc.

The invention has for its principal object to provide a current motor in which a plurality of current operated blades are carried by endless tread chains in a novel manner and are turned by unique means to inactive position, when the ends of their strokes have been reached.

With the foregoing and minor objects in view, the invention resides in the novel construction and combination of parts herein-after described and claimed, the descriptive matter being supplemented by the accompanying drawings.

Figure 1 is a top plan view of a current motor constructed in accordance with my invention.

Figure 2 is a side elevation.

Figure 3 is a vertical transverse sectional view as indicated by line 3—3 of Fig. 2.

Figure 4 is a detail elevation showing the manner of connecting the blades with the endless belts or chains.

Figure 5 is a detail sectional view as indicated by line 5—5 in Fig. 4.

Figure 6 is a detail view showing more particularly the action of the blades as they reach the end of their working strokes.

In the drawings above briefly described, 45 the numeral 1 designates a horizontally elongated rectangular frame provided with appropriate end bars 2 extending horizontally across the upper and lower portions of the frame. The end bars 2 at the inlet end 50 of the frame are offset from each other horizontally and a plurality of inclined grating bars 3 are secured at their ends to said end bars so as to form a guard to prevent submerged ice and any other solid matter from

entering the frame and interfering with the working parts therein.

The frame 1 includes a pair of longitudinal side bars 4 upon which bearings 5 are mounted for a pair of transverse horizontal shafts 6. The bearings at one end of the frame are preferably adjustable by means of nuts, screws or the like 7.

Each shaft 6 is equipped with a pair of horizontally spaced guide wheels 8 which are preferably in the form of sprockets, and a pair of endless belts, here shown in the form of chains 9, are trained around the wheels 8, being provided with horizontal upper and lower reaches. At suitably spaced intervals, rods 10 extend between the chains 9 and are 70 suitably attached at their ends thereto, and upon these rods, the bearings 11 of a plurality of blades 12, are pivotally mounted, said bearings being preferably secured to the blades by eye-bolts 13. The blades 12 75 of the lower reach of the chains 9 are adapted to extend upwardly as shown clearly in Fig. 2, to be acted on by the current, and flexible braces 14, preferably in the form of chains, are provided to hold said blades 80 in operative position. One end of each of the braces 14 is connected with the adjacent eye-bolt 13, while the other end thereof is connected with the outer edge of the next adjacent blade 12, by an eye-bolt or the like 15. By comparing the upper and lower portions of Fig. 2, it will be seen that while the chains 14 hold the blades 12 in operative 85 position on the lower reaches of the chains 9, they permit feathering of said blades upon 90 the upper reaches of the chain, so that there will be no obstruction to their passage through the water against the current.

For turning the blades outwardly from their operative position when they reach the 95 ends of their working strokes, I provide a wheel 16. This wheel is secured on the rear-most of the shafts 6, between the guide wheels 8 of said shaft and it is positioned in the path of the blades 12 as shown clearly 100 in Fig. 2. The result is that as the blades strike the wheel (see Fig. 6) they must tilt as shown in full lines in this figure, the tilting increasing as the chains 9 continue to move in the direction indicated by the arrow 105 16. When the blades have tilted approximately to the extent shown by dotted lines in Fig. 6, the water current acts on said blades

and throws them outwardly to the position indicated at P in Fig. 2. Thus, as the blades travel against the current during their return strokes, they do not materially retard the operation of the motor.

From the foregoing, taken in connection with the accompanying drawings, it will be seen that I have produced a comparatively simple and inexpensive, yet a highly efficient and desirable current motor, particular attention being directed to the manner of mounting the blades 12 and turning them to inactive position at the ends of their strokes.

Since probably the best results may be obtained from the details disclosed, these details may be followed if desired. I wish it understood however that within the scope of the invention as claimed, numerous minor changes may be made.

I claim:

1. A current motor comprising a frame

having a pair of laterally spaced guide wheels at each end, a pair of endless belts trained around said wheels and having horizontal reaches, a plurality of blades extending between said belts and pivoted at their outer edges thereto, the blades of the lower reaches of said belts being adapted to extend upwardly from said reaches to be acted on by the current, and a blade-turning wheel between the guide wheels at one end of the frame, said blade-turning wheel being in the path of the upwardly extending blades for the purpose set forth.

2. A structure as specified in claim 1, together with shafts extending between and carrying said guide wheels, said blade-turning wheel being mounted centrally on one of said shafts.

In testimony whereof I have hereunto set my hand.

CLARENCE BENTON JORDIN.
